(57) CLAIM

The ornamental design for night vision goggles as shown and described.

DESCRIPTION

FIG. 1 is a front, right perspective view of the night vision goggles;

FIG. 2 is a rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown in the drawings depict portions of the night vision goggles that form no part of the claimed design.
